(57) **CLAIM**

The ornamental design for a solar dock light, as shown and described.

DESCRIPTION

FIG. 1 is a top perspective view of a solar dock light design showing my new design.

FIG. 2 is a bottom perspective view of a solar dock light.

FIG. 3 is a front view of a solar dock light.

FIG. 4 is a rear view of a solar dock light.

FIG. 5 is a left side view of a solar dock light.

FIG. 6 is a right side view of a solar dock light.

FIG. 7 is a top view of a solar dock light; and,

FIG. 8 is a bottom view of a solar dock light.

Any shading and cross-hatching are not features of the design but are utilized to illustrate the surface contours of the solar dock light design in the drawings.
